UNITED STATES PATENT OFFICE.

JOSEPH A. IMHOF, OF NEW YORK, AND JOHN CHARTERS, OF ASTORIA, NEW YORK, ASSIGNORS TO INVISIBLE COLOR PRINT CORPORATION, OF NEW YORK, N. Y., A CORPORATION OF NEW YORK.

PROCESS OF MAKING PRINTS.

Original application filed October 31, 1922, Serial No. 598,081. Divided and this application filed February 7, 1923. Serial No. 617,457.

To all whom it may concern:

Be it known that we, JOSEPH A. IMHOF, a citizen of the United States, and a resident of the city of New York, in the borough of Manhattan, county and State of New York, and JOHN CHARTERS, a citizen of the United States, and resident of Astoria, Long Island City, in the county of Queens and State of New York, have invented certain new and useful Improvements in Processes of Making Prints, of which the following is a specification.

This invention relates to an improved process of making prints and is a division 15 of application Serial No. 598,081, filed October 31, 1922.

In the prior art of making prints, hidden images have been produced in various ways and have been rendered visible by the use 20 of chemicals. The main object and feature of the present invention is to render the hidden object visible by the application of water without the use of special chemicals.

In the accompanying drawings the invention 25 is embodied in a preferred form in which—

Figs. 1, 2, 3 and 4 are diagrammatic views showing the steps of the invention for producing a hidden image and the revealing 30 of the same.

1 indicates a printing surface of paper or other material capable of receiving impressions. In Fig. 2 this surface is shown as having received an impression of an invisible image 3 indicated for convenience by the word "President" in dotted outline. This image is made preferably with an impression of translucent varnish and is therefore both insoluble in water and invisible 35 and may be made either from a solid form or from a half-tone or the like such as a Ben Day plate. If desired the varnish may be slightly tinted so as to match as nearly as possible the tone or color of surface 1 before printing. The tint thus used 40 may be a white oil ink.

2 indicates an overlying impression, indicated for convenience by section lines,

which forms a visible image. This impression 2 is made with ink consisting wholly 50 of or carrying latent coloring matter such as aniline dye soluble in water as explained in Patent No. 1,384,663, dated July 12, 1921. It will be understood that a single color only need be used and that this color may 55 be the same as the oily body carrying the color, if such be employed. And further that the printing may be solid as when produced from a printing surface of uniform height or the printing may be done from 60 half-tone plates or the like such as Ben Day plates.

The visible image thus disguises the subjacent invisible image which latter, however, is caused to emerge when water is applied as shown in Fig. 4 by contrast of color. 65 It will be understood that the invisible image printed in varnish tends to prevent the sinking in of the ink or coloring matter of the visible image and that consequently 70 when water is applied the ink overlying the invisible image is washed off in whole or in part thereby setting up the color contrast necessary to reveal the invisible image.

We claim:

1. The method of disguising and of subsequently rendering apparent a design in a printed product which consists in imprinting, on a surface, a substantially invisible image formed by an impression insoluble in 80 water, then imprinting upon said surface in super-imposed relation to the first impression, another and visible image formed by an impression containing matter soluble in water, and then applying water to said surface to dissolve the second impression and to remove it from that part of the surface carrying the invisible image to thereby render the latter visible by contrast in color with the initially visible image. 85

2. The method of disguising and of subsequently rendering apparent a design in a printed product which consists in imprinting, on a surface, a substantially invisible image formed by an impression of translucent varnish, then imprinting upon said sur- 90 95

face in superimposed relation to the first impression, another and visible image formed by an impression containing matter soluble in water, and then applying water to said surface to dissolve the second impression and to remove it from that part of the surface carrying the invisible image to

thereby render the latter visible by contrast in color with the initially visible image.

Signed at New York city, in the borough ¹⁰ of Manhattan, county and State of New York, this 29th day of Jan., 1923.

JOSEPH A. IMHOF.
JOHN CHARTERS.
